UNITED STATES PATENT OFFICE.

HENRY A. NOAR, OF PHILADELPHIA, PENNSYLVANIA.

DYEING-MACHINE.

1,052,168.

Specification of Letters Patent. Patented Feb. 4, 1913.

Application filed March 19, 1912. Serial No. 684,721.

To all whom it may concern:

Be it known that I, HENRY A. NOAR, a citizen of the United States, residing at Philadelphia, in the county of Philadelphia and State of Pennsylvania, have invented certain new and useful Improvements in Dyeing-Machines, of which the following is a specification.

This invention relates to that class of dyeing machines wherein the articles to be dyed, particularly hanks of yarn, are supported within a vat and wherein dye liquor is caused to circulate and flow through the space occupied by the yarn. Heretofore, in machines of this class, the hanks of yarn have been suspended in elongated condition and supported only at the top, or the hanks of yarn have been maintained in elongated condition by being supported at each end by sticks or shafts extending through the same. In each instance where the elongated hanks of yarn are held at one or both ends the dye liquor has been caused to flow through the elongated hanks longitudinally thereof. This operation has been objectionable for the reason that the dye liquor flowing through the hanks of yarn longitudinally thereof does not penetrate the fiber to produce as fine a finished product as to uniformity of coloring, luster, open fiber, loftiness, etc., as is desirable, and for the further reason that, where the hanks of yarn are held at one end only, the flow of the dye liquor causes the hanks to buckle and mat together in a manner to interfere with the flow of the dye liquor and the proper subjection of the yarn thereto.

The object of my invention is to overcome the objections just mentioned and to provide a dyeing machine of the class to which my invention relates, of novel, simple and efficient construction which may be operated to dye hanks of yarn in a manner to give the superior results obtained in hand tub dyeing as to uniformity of coloring, luster, open fiber, loftiness, etc., and in which the desired results may be obtained from indentrene or vat colors where a total submerging is required and in which bright acid colors may be produced where only partial submerging is needed to allow oxidation in the open air. As generally stated, I accomplish my object by constructing and arranging the parts of the machine so that the hanks of yarn may

be supported in elongated condition and in spaced relation to each other in a vat and so that the dye liquor may be caused to flow through the elongated hanks in a direction transversely thereto while the hanks are caused to revolve or travel longitudinally of the threads thereof and transversely to the flow of the dye liquor.

The invention consists in the various novel features of construction and combinations of parts hereinafter fully described and particularly claimed.

In the accompanying drawings, illustrating my invention: Figure 1, is a plan view of a dyeing machine, showing one form of embodiment of my invention. Fig. 2, is a perspective view of one of the yarn supporting sticks. Fig. 3, is a longitudinal section, on line 3—3 of Fig. 1. Fig. 4, is a transverse section, on line 4—4 of Fig. 3. Fig. 5, is a transverse section, on line 5—5 of Fig. 3. 75

Referring to the drawings, 6 designates an elongated vat comprising a bottom, side walls and end walls, as shown. The vat 6 is provided with two vertically-arranged partition walls extending transversely between the side walls thereof and dividing the vat into two end chambers 8 and a central chamber 9 between the end chambers 8. The vat 6 is adapted to contain the dye liquor and the partition walls 7 are provided with perforations 10 affording communication between the end chambers 8 and the central chamber 9 so that the dye liquor may flow from one chamber to the other. 80 85

During the dyeing operation, hereinafter explained, the dye liquor is caused to flow horizontally through the central chamber 9 and for this purpose I provide the following: Extending over the end walls of the vat 6 and into the end chambers 8 are pipes 11 95 the inner open ends of which are directed toward each other and toward the partition walls 7. The pipes 11 extend from the vat 6 to a suitable pump or circulating device 12 which may be of any approved type. One 100 pipe 11 is connected to the outlet of the pump 12 and the other pipe 11 is connected to the inlet of the pump, whereby, when the pump 12 is operated, the dye liquor will be drawn from one end chamber 8 through one 105 pipe 11 and forced into the other end chamber 8 through the other pipe 11, thereby causing the dye liquor to circulate through

the vat 6, the partitions 7 therein, the pipe 11 and the pump 12 and to flow horizontally through the central chamber 9.

The central chamber 9 is adapted to receive the hanks of yarn or other articles to be dyed; and to properly support hanks of yarn within the chamber 9, while being dyed, I provide a frame or carrier 13, movable vertically into and from the chamber 9. The frame of the carrier 13 comprises upper and lower horizontal bars 14 and 15, respectively, which extend parallel to each other longitudinally of the vat 6, transverse bars 16 connecting the ends of the upper bars 14, vertical bars 17 connecting the ends of the upper bars 14 with the ends of the lower bars 15, and transverse bars connecting the lower portions of the vertical bars 17.

In order that the carrier 13 may be moved vertically into and from the vat 6, I connect the upper bars 14 with spaced transverse bars 19 which are provided with upwardly extending straps or brackets 20 adapted to be engaged by hooks 21 on the lower ends of chains 22 depending from a suitable mechanism (not shown) arranged above the vat 6 for raising and lowering the carrier 13.

The carrier 13 is provided with an upper set of yarn-supporting sticks 23 and a lower set of yarn-supporting sticks 24 corresponding in number with and being located directly below the sticks of the set 23. Thus the sticks of the two sets are arranged in pairs, the stick 23 of each pair being directly above the sticks 24 thereof. Each pair of sticks 23 and 24 supports a number of hanks of yarn 25, the hanks extending around the sticks and being held thereby in the elongated condition, shown, as well as being supported thereby in the vertical positions shown.

The lower sticks 24 are made round in cross section and they extend between and are rotatably mounted in the lower bars 15 of the carrier 13.

The upper sticks 23 extend between the upper bars 14 of the carrier 13; and one end and the main body of each upper stick 23 is made square and the other end thereof is made round. The round end is mounted to rotate in one of the bars 14 and the square end is inserted into a square opening in the hub 26 of a worm wheel 27. The worm wheel 27 for each stick 23 is arranged outwardly of one of the bars 14 and the hub 26 of the worm wheel extends through and is rotatably mounted in the bar 14, whereby, when the worm wheels 27 are rotated the sticks 23 will be rotated.

Each worm wheel 27 co-acts with a worm 28 on a horizontal shaft 29 which extends parallel to the adjacent bar 14 and is mounted to turn in suitable bearings secured thereto. The shaft 29 is provided with a sprocket wheel 30 driven by a chain 31 from

a sprocket wheel 32 on a short horizontal shaft 33 which is mounted to turn in bearings 34 secured to and rising from the adjacent bar 14 of the carrier 13. One end of the shaft 33 extends outwardly beyond one of the bearings 34 and is provided with a clutch member 35 adapted to be actuated, as hereinafter described, to rotate the shaft 33 and thereby rotate the yarn-carrying sticks 23 through the gearing just described.

The actuating mechanism for the yarn-carrying sticks thus far described is mounted on the carrier 13 and is carried thereby when the carrier is moved into and from the vat.

When the carrier 13 is within the chamber 9, it is supported therein by the transverse bars 19 resting on the sides of the vat 6 and connected to the carrier 13 by straps 19^a; and when the carrier 13 is in this position, the shaft 33 is in axial alinement with a horizontal shaft 36 which is rotatably mounted in bearings 37 and 38 secured to the vat 6. The inner end of the shaft 36 carries a clutch member 40 adjacent the clutch member 35 when the carrier 13 is within the vat. The hub of the clutch member 40 is splined on the shaft 36 to cause it to be rotated therewith and to permit it to be moved longitudinally thereon into and from engagement with the clutch member 35. The clutch members 35 and 40 are each provided with projecting teeth, and the teeth of the member 40 are adapted to enter the spaces between the teeth of the member 35 when the member 40 is moved into engagement with the member 35, thereby causing the member 35 to be rotated by the member 40 and the yarn-carrying sticks 23 to be rotated by the power applied to the shaft 36.

To shift the clutch member 40 into and from engagement with the member 35, I provide a hand lever 41 fulcrumed, at 42, to an arm extending from the bearing 37. The upper end of the lever 41 is provided with a suitable handle, and the lower end of the lever is bifurcated and embraces the hub of the clutch member 40 and is provided with inwardly extending pins entering a circumferential groove in the hub of the member 40. It will thus be seen that the hub of the member 40 may be moved longitudinally on the shaft 36 by moving the lever 41 and that the member 40 is free to rotate with the shaft.

The machine is employed with suitable automatic mechanism for causing the shaft 36 to reverse its direction of rotation at certain intervals thereby causing each hank of yarn to reverse its direction of movement at certain intervals; and the gearing between the shaft 36 and the sticks 23 is such that each time the hanks of yarn make a complete turn around the sticks 23 and 24 the

hanks are caused to reverse their movements. This operation maintains the hanks of yarn in proper position notwithstanding the well known twist in each hank tending to throw it out of position.

To actuate the shaft 36 and to cause it to automatically reverse its direction of rotation, I provide the following mechanism: Mounted to turn loosely on the shaft 36 and 10 facing each other are two bevel gear wheels 45 which coact with a bevel gear wheel 47 fixed on a shaft 48 extending at right angles to the shaft 36 and mounted to turn in bearings 49 on the vat 6. This shaft 48 is provided with a sprocket wheel 50 actuated by a chain 51 from an outside source of power to rotate the shaft 48. Splined on the shaft 36 is a clutch collar 52 adapted to be moved alternately into engagement with the gear 15 wheels 45. The collar 52 is provided with projecting teeth adapted to enter spaces between projecting teeth on the gear wheels 45 and thereby alternately clutch them to the shaft 36, when the collar 52 is moved 20 from one gear wheel to the other and back again. The collar 52 is provided with a circumferential groove into which extends a pin on the lower end of a lever 53 which is fulcrumed at 54 on an arm extending from 25 the bearing 37. The upper portion of the lever 53 has a weight 54 pivoted at 55 thereto. The weight is adapted to be moved from side to side of its center of gravity on the pivot 55 by projections 56 extending 30 from plates 57 carried by a horizontally reciprocative gear rack 58 mounted to slide in a bracket in the vat 6. The weight 54 is provided with two spaced shoulders 59 adapted to alternately engage the upper end 35 of the lever 53. When the weight is moved from side to side of its center of gravity its shoulders 59 alternately strike the lever 53 and alternately move it from side to side and cause it to alternately engage the clutch 40 collar 52 with the gear wheels 45 and 46. The gear rack 58 coacts with a gear wheel 59 on a shaft 60 which is mounted to turn in bearings on the vat 6. The shaft 60 carries a worm wheel 61 engaged by a worm 62 45 on the shaft 36.

From the construction just described it will be seen that when the weight 54^a rests on one side of its center of gravity and holds the clutch collar in engagement with one of 50 the gear wheels 45 to turn the shaft 36 in one direction, the worm 62 will actuate the shaft 60 and cause the gear wheel 59 to move the rack 58 until one of the projections 56 moves the weight 54 to the other 55 side of its center of gravity and shifts the clutch collar 52 into engagement with the other gear wheel 45, thereby causing the shaft 36 and worm 62 to rotate in a reverse direction and move the rack 58 in a reverse 60 direction until the other projection 56 en-

gages the weight 54^a to shift the clutch collar back to the wheel 45 from which it was previously moved and again reverse the direction of rotation of the shaft 36.

In order to heat the dye liquor within the vat 6, I provide perforated steam pipes 65 which extend through the lower portion of the vat 6 and are connected to a steam supply pipe 66 which extends over one side of the vat and is provided with a controlling valve 67.

The operation of the machine, briefly described, is as follows: The carrier 13 is raised from the vat 6 and the hanks of yarn are applied to the sticks 23 and 24. This is accomplished by first withdrawing the sticks endwise from the bars 14 and 15, respectively, on one side of the carrier, and then projecting the sticks back into the carrier and into the positions shown, as the hanks of yarn are applied thereto. After the carrier is supplied with yarn, the carrier is lowered into the position shown within the central chamber 9 and into the dye liquor within the vat. Power is now applied to the driving shaft 48 thereby actuating the pump or circulating device 12 to cause the dye liquor to circulate as previously explained. During the circulation of the dye liquor, the hanks of yarn are maintained in the elongated condition shown by the sticks 23 and 24 and the dye liquor is caused to flow horizontally through the chamber 9 and through the elongated hanks of yarn, in a direction transversely or at right angles thereto, thus accomplishing the principal object of my invention as previously mentioned. While the dye liquor is thus circulating through the vat, the lever 41 is operated to engage the clutch member 40 with the clutch member 35, thus causing the upper yarn-supporting sticks 23 to rotate first in one direction and then in a reverse direction through the reversing gears 45, as previously explained. The actuation of the sticks 23 causes the hanks of yarn 25 to travel around the axes of the sticks 23 and 24 and to periodically reverse their direction of movement while the hanks are maintained in the elongated condition, thereby presenting all parts of the hanks to the circulating dye liquor away from the sticks 23 and 24 and insuring a thorough subjection of all parts of the yarn to the action of the dye liquor. The perforations 10 in the partition walls 7 are arranged in such relation to the space occupied by the hanks of yarn within the chamber 9, and the inner ends of the pipes 11 as to cause a substantially uniform flow of the dye liquor through all parts of the space occupied by the yarn, resulting in a uniform action of the dye liquor on all the yarn carried by the carrier 13. After the yarn has been properly subjected to the dye liquor, the lever 41

is operated to release the clutch member 40 from the member 35 and the carrier 13 is raised from the vat to remove the hanks of yarn therefrom or to transfer the carrier 5 with the yarn thereon to another vat for another operation when required.

I claim:

1. In a dyeing machine, the combination of a vat, means for supporting elongated 10 hanks of yarn within said vat and maintaining said hanks in elongated condition, and means operative to cause dye liquor to flow through said vat in a direction transverse to the elongated hanks of yarn supported 15 therein.
2. In a dyeing machine, the combination of a vat, means for supporting elongated hanks of yarn within said vat and maintaining said hanks substantially in vertical 20 positions, and means operative to cause dye liquor to flow horizontally through that portion of the vat occupied by the hanks of 25 yarn supported therein.
3. In a dyeing machine, the combination of a vat provided with partition walls dividing it into two end chambers and a central chamber therebetween, the partition walls having openings therein affording communication between the central chamber 30 and the two end chambers, means for supporting elongated hanks of yarn within the central chamber and maintaining said hanks substantially in vertical position, and means operative to cause dye liquor to flow from 35 one end chamber through the partition walls and the central chamber to the other end chamber.
4. In a dyeing machine, the combination of a vat provided with partition walls dividing it into two end chambers and a central chamber therebetween, the partition walls having openings therein affording communication between the central chamber and the two end chambers, means for supporting 40 elongated hanks of yarn within the central chamber and maintaining said hanks substantially in vertical position, a pump, a pipe leading from the pump outlet to one end chamber, and a pipe leading from the 45 pump inlet to the other end chamber, whereby dye liquor may be caused to circulate through said pipes and said chambers by the operation of the pump.
5. In a dyeing machine, the combination of a vat, a pair of spaced sticks supported 50 within the vat and adapted to support hanks

of yarn extending around the same, said sticks being adapted to maintain said hanks of yarn in elongated condition, means operative to rotate one of said sticks, and 60 means operative to cause dye liquor to flow through said vat in a direction transversely to the elongated hanks of yarn supported therein.

6. In a dyeing machine, the combination 65 of a vat, a pair of spaced sticks supported in said vat one above the other and adapted to support hanks of yarn extending around the same, said sticks being adapted to maintain said hanks of yarn in elongated condition 70 and substantially in vertical positions, means operative to rotate one of said sticks, and means operative to cause dye liquor to flow horizontally through that portion of the vat occupied by the hanks of 75 yarn supported therein.

7. In a dyeing machine, the combination of a vat provided with partition walls dividing it into two end chambers and a central chamber therebetween, the partition 80 walls having openings therein affording communication between the central chamber and the two end chambers, a pair of spaced sticks supported in the central chamber one above the other and adapted to support 85 hanks of yarn extending around the same, said sticks being adapted to maintain said hanks of yarn in elongated condition and substantially in vertical positions, means operative to rotate one of said sticks, and 90 means operative to cause dye liquor to flow from one end chamber through the partition walls and the central chamber to the other end chamber.

8. In a dyeing machine, the combination 95 of a vat, a pair of spaced sticks supported within the vat and adapted to support hanks of yarn extending around the same, said sticks being adapted to maintain said hanks of yarn in elongated condition, means operative to rotate and to automatically reverse 100 the direction of rotation of one of said sticks, and means operative to cause dye liquor to flow through said vat in a direction transversely to the elongated hanks of 105 yarn supported therein.

In testimony whereof I affix my signature in presence of two witnesses.

HENRY A. NOAR.
